METHOD AND APPARATUS FOR
COMBINING STRANDS

Vaughn L. Johannessen, Cranford, N. J., assignor
to Western Electric Company, Incorporated,
New York, N. Y., a corporation of New York

Application June 1, 1935, Serial No. 24,543

14 Claims. (Cl. 117—46)

This invention relates to a method and apparatus for combining strands and more particularly to a method and apparatus for making multiconductor electrical cables for use in the communication arts.

In multiconductor cables for telephone use it is essential in some instances that the conductors of a given group within the cable shall not run parallel to the conductors of another given group for any substantial distance to obviate certain difficulties arising out of electrical capacity and mutual induction effects between the groups.

An object of the present invention is to provide a method and means for making a multiconductor cable in which one group of conductors is stranded together spirally with a lay of a predetermined pitch while another group of conductors associated therewith is stranded with a lay of varying pitch.

One embodiment of the invention contemplates a method and an apparatus for laying up multiconductor cables which comprise steps and means for laying up an inner or core group of conductors stranded together with substantially constant pitch while simultaneously laying another group or shell of conductors around the core group with a lay having a regularly cyclically recurrent variation, or vice versa, or in which both groups have cyclically varying pitch but of unlike values.

Other objects and characteristic features of the invention will appear from the following detailed description of one embodiment thereof taken in connection with the accompanying drawings in which the same reference numerals are applied to identical parts in the several figures and in which

Fig. 1 is a diagrammatic broken perspective view in side elevation of a cabling machine constructed in accordance with the invention;

Fig. 2 is a broken view in side elevation of a portion of conductor cable formed in the apparatus of Fig. 1;

Fig. 3 is a view of the cable in end elevation;

Fig. 4 is a view similar to Fig. 1 of a modified form of the machine;

Fig. 5 is a view similar to Fig. 2 of a cable formed therein;

Fig. 6 is a view similar to Fig. 1 of another form of machine, and

Fig. 7 is a view similar to Fig. 2 of a cable formed therein.

In the embodiment herein disclosed, a supply reel carrier generally indicated by the numeral 20 comprises a left hand annular member 21 and

longitudinal tie members 17 extending to the right. A plurality of conductor strand supply reels (not shown) is supported in the supply reel carrier 20 and the carrier is rotatably mounted in a standard 18 and is driven in rotation about a horizontal axis by means not shown. The construction and details of the carrier 20 and its drive are not a part of or pertinent to the present invention and so are not disclosed here. Such devices are well known in the art of combining strands, e. g. U. S. Patent 1,866,272, issued to George A. Seeley, July 5, 1932, discloses a form of supply reel carrier and drive well adapted for use in connection with the apparatus herein disclosed.

Strands 22 drawn from the supply reels of the carrier 20 pass freely through the central aperture of the ring 21 and then individually through corresponding perforations 23 formed in a circular distributor disc 24 rotatably supported in a fixed standard 19. The perforations 23 may preferably be arranged in concentric circles corresponding to an inner or core group A and an outer or shell group B of strands in the completed cable.

The distributor disc 24 is formed with a peripheral gear 25 which engages with a pinion 26 rigidly mounted on a drive shaft 27 driven by means not shown. A clutch disc 28 is mounted on the shaft 27 to be slidable thereon and is keyed thereto to rotate therewith by a key 29. The disc 28 is formed with a peripheral groove in which is located a ring 30. The rear forked end 31 of a lever 32 is secured to the ring 30 by pins 33, the lever being pivoted at 34 on a stationary standard 35. The near end of the lever 32 is secured to one end of a tension spring 36, the other end of which may be conveniently secured to the standard 19.

Clutch pins 37 are mounted in the left face of the disc 28 for coaction with corresponding recesses 38 formed in the right side of a pinion 39 mounted on the shaft 27 and freely rotatable thereon. The pinion 39 engages with a peripheral gear 40 formed on a second distributor disc 41 rotatably mounted in a standard 42 and parallel to the disc 24. This second distributor disc 41 is formed with a relatively large axial perforation 43 and with a concentric ring of perforations 44 corresponding to the individual strands of the outer or shell group B which pass through the perforations 44. The conductor strands of the inner or core group A pass as an undivided group freely through the axial perforation 43. All of the strands pass from

the distributor disc 41 to a twisting and compacting die 45 such as is customary in the art and thence to propelling mechanism not shown, of any suitable construction.

5 A cam 46 is formed on or secured to the left face of the disc 24 and is slidably engaged by the right end of a cam rod 47 conveniently slidably mounted in the standards 19 and 35. The left end of the rod 47 abuts against the 10 near arm of the lever 32, and a push block 48 is rigidly mounted on the rod 47 to move therewith.

15 A rod 49 is slidably mounted in the block 48 and in the standard 35 and has stop collars 50 and 51 adjustably secured thereon, as by jam screws 52 and 53. A spiral compression spring 54 surrounds the rod 49 and abuts against the collar 51 and the block 48. The left end of the rod 49 is adapted to enter a corresponding recess 55 formed in the right face of the disc 41.

20 In operation the drive shaft 27 may be thought of as rotating continuously and unvaryingly counterclockwise as seen from the right, and the strands 22 as advancing continuously and unvaryingly through the apparatus from right to left.

25 The pinion 26 drives the distributor disc 24 in clockwise rotation and the strands being brought together at the die 45, this action tends to impose a uniform left hand twist on all the strands 22. Since the strands of the inner or core group A pass freely through the perforation 43 to the die 45, these strands are in fact so stranded together and lie in the finished cable with a uniformly pitched left hand spiral lay.

30 The strands of the outer or shell group B however pass individually through the perforations 44 of the distributor disc 41 and are therefore subjected to the action of this disc as well as of the disc 24. At a certain point in each revolution of the disc 24 the rod 47 slips off the abruptly terminated trailing end 56 of the cam 46, and the spring 36 draws the near arm 45 of the lever 32 and therewith the rod 47 to the right. The far or rear end of the lever 32 moves to the left carrying the ring 30 and clutch disc 28 with it until the pins 37 engage in the recesses 38 rotating the pinion 39 and thus driving the distributor disc 41 in clockwise rotation. At the same time the block 48 moves to the right with the rod 47 drawing the rod 49 also to the right against the urge of the spring 54 and releasing the left end of the rod 49 from the recess 55 just before the clutch pins 37 engage in the recesses 38.

35 The gearings 25, 26 and 39, 40 are so proportioned that the disc 41 is driven at a different speed than the disc 24. For discussion let it be assumed that disc 41 rotates at twice the speed of disc 24. The strands of the outer group B then are twined around the strands of the inner group A twice as fast as the strands of the inner group A are stranded together so long as the disc 41 is rotating.

40 This effect continues during one half revolution of disc 24 or one whole revolution of disc 41 until the tapering advance end 57 of the cam 46 picks up the rod 47 and shifts it to the left against the tension of the spring 36. The block 48 compresses the spring 54 tending to drive the rod 49 to the left and pressing the end of rod against the right face of the disc 41, the resulting friction acting as a brake to slow

5 the disc down until the end of the rod enters the recess 55 and stops the disc entirely. Meantime the first motion of the rod 47 to the left has actuated the lever 32 to disengage the clutch pins 37 from the recesses 38 thus leaving the disc 41 free to be braked and stopped as described. At this time the strands of the outer group B have shifted around on the unvaryingly pitched strands of the inner group A by about one half the circumference of the cable. The 10 disc 41 being now stationary while the disc 24 continues to rotate unvaryingly, the inner group A overtakes the outer group B in lay during the second half revolution of disc 24 until the rod 47 slips off the abrupt trailing end 56 15 of the cam and the entire cycle begins again.

10 Thus with each rotation of the disc 24, one complete turn of uniform lay is imposed by the action of this disc upon the length of the strands in the inner group A entering the die 45 during 20 the one rotation of the disc. At the same time, substantially the same length of the strands of the outer group B also receives one complete turn of lay, but this lay is nonuniform in pitch, all of it being put in one half of the length, while 25 the disc 41 is rotating, and no spiral being put into the other half length of the outer group B while the disc 41 is stationary. In the completed cable therefore the strands of the inner or core group A lie with a continuous unvarying lay 30 while the strands of the outer or shell group B lie with a lay whose total number of turns in any given length of the cable is the same as that of group A, but whose pitch varies cyclically from infinite pitch to twice the constant pitch of 35 group A.

35 By altering the angular length of the cam 46 on the disc 24, the character of the twist of group B may be widely altered without affecting its cyclicity.

40 The embodiment of the machine shown in Fig. 4 is a modification of that described above, which produces a cable of the structure shown in Fig. 5. This machine is derived from that of Fig. 1 substantially by inverting the drive relation of the 45 discs 41 and 24. It is thought that Fig. 4 is clearly self-explanatory after the detailed description of Fig. 1 and that no complete and detailed description in words is here necessary except as follows.

50 In Fig. 4 disc 24 is driven in intermittent clockwise rotation (as seen from the right) by the pinion 39 under the control of the clutch 37, 38, the lever 32, the bar 47, the spring 36 and the cam 46, while the disc 41 is driven in the same 55 direction in continuous uniform motion.

55 The inner or core group C of strands is alternately spiralled and laid straight by the disc 24, since they pass freely through the aperture 43 to the die 45. Although the strands of the outer 60 or shell group D are moved intermittently between the discs 24 and 41, this nonuniform motion does not pass the disc 41, and these strands are laid by the disc 41 about the core group at the die 45 with uniform and unbroken pitch. 65 Thus the product has the general characteristics shown in Fig. 5.

70 In each of the two machines described above the average pitches of the inner and outer groups of strands must be the same as no cumulative 70 twist may be put into the strands relatively to each other between the discs 24 and 41. In Fig. 6 is illustrated a modified form of the machine in which this is not a necessary limitation, and in which more than two groups of strands may be 75

combined in distinct layers of the completed cable, each layer or group having a lay distinct in character from the others.

In this embodiment the mechanism mounted in 5 and between the standards 18, 19 and 42 is substantially the same as that shown in Fig. 4 and is operative to strand the core group C and middle shell group D of the completed cable shown in Fig. 7 in the same manner as the groups C and D 10 of Fig. 5 are laid up by the machine of Fig. 4. In Fig. 6, there is added mechanism which is operative to strand a third or outer shell group F (Fig. 7) about the group E, this outer group differing in length of pitch, if desired, as well as 15 in character of lay from either or both of the other groups.

This additional mechanism comprises a standard 142 having a distributor disc 141 rotatably mounted therein and provided with a central 20 aperture 143 through which the strands of the core group and the middle shell group pass freely from the aperture 43 and the apertures 44 to the die 45. The disc 141 may be formed as an elliptical gear which meshes with a complementary elliptical gear 139 rigidly mounted on a shaft 127 driven from or driving the shaft 21 through gears 170, 171 and 172. A cage 160 is rigidly mounted on the rear face of the disc 141 to rotate therewith and carries a plurality of 30 supply reels 161 from which the strands of the group E are drawn and pass through individual perforations 144 to the die 45.

The ratio of the speed of the shaft 127 to that of the shaft 21 may be given any desired value 35 by suitably proportioning the gears 170, 171 and 172 which in turn will determine the ratio of the pitch of group F to that of groups C and D.

It is easily seen therefore that this apparatus 40 will strand a cable as shown in Fig. 7 in which the core group C has cyclically abruptly varying pitch, the middle shell group D has unvarying pitch of the same value, and the outer shell group F has cyclically smoothly varying pitch of a value independent of that of groups C and D.

45 By failing to thread strands through the apertures 44, a cable may be produced having two groups, each cyclically varying in pitch, and independent of each other as to pitch value. By omitting to thread strands through the aperture 50 43, a cable may be produced analogous to that of Fig. 2 but with the two groups independent as to pitch value.

It is to be noted that by the phrase "completed cable" in this description, the product issuing 55 from the die 45 is meant. In practise this cable as a whole may undergo further twisting which will change the outer appearance but will not change the pitch and lay relation of the core and shell groups to each other.

60 In either machine, the fate of the cable after entering the die 45 is not within the field of this invention. It may be desired however, in some instances, to impose additional twist thereafter which may be accomplished, for example, by the means shown in U. S. Patent 1,866,272 already referred to.

The embodiments of the invention herein disclosed are illustrative only and may be widely modified and departed from without departing 70 from the spirit and scope of the invention as pointed out in and limited only by the appended claims.

What is claimed is:

1. A method of combining strands to form a 75 cable which comprises stranding a plurality of

strands with constant pitch, stranding a second plurality of strands with cyclically varying pitch, and positioning one of the pluralities as a shell about the other as a core.

2. A method of combining strands to form a 5 cable which comprises stranding a plurality of strands with cyclically varying pitch, stranding a second plurality of strands with a different cyclically varying pitch, and positioning one of the pluralities as a shell about the other as a 10 core.

3. A method of combining strands to form a cable which comprises stranding a plurality of strands while imposing a lay of uniform pitch upon one part of the plurality and a lay of 15 cyclically varying pitch upon another part of the plurality.

4. An apparatus for combining strands to form a cable, which comprises means to strand a plurality of strands with one kind of pitch, means to strand a second plurality of strands with another kind of pitch, and means to position one of the pluralities as a shell about the other as a 20 core.

5. An apparatus for combining strands to form a cable, which comprises means to strand a plurality of strands with a lay of constant pitch, means to strand a second plurality of strands with a lay of cyclically varying pitch, and means to position one of the 25 pluralities as a shell about the other as a core.

6. An apparatus for combining strands to form a cable, which comprises means to strand a plurality of strands with a lay of cyclically varying pitch, means to strand a second plurality of 30 strands with a lay of differently cyclically varying pitch, and means to position one of the pluralities as a shell about the other as a core.

7. An apparatus for combining strands to form a cable, which comprises means to strand a plurality of strands in combination with means to simultaneously impose a lay of cyclically varying pitch upon a part of the plurality while the entire plurality is being stranded.

8. An apparatus for combining strands to form a cable which comprises means to revolve a plurality of strands at constant speed about a common axis, means to revolve a second plurality of strands at varying speed about the same axis, and means to combine the two pluralities together and to annul their revolution, whereby all the strands are intertwined together and those of the first plurality have constant pitch and those of the second plurality have varying 55 pitch.

9. An apparatus for combining strands to form a cable which comprises means to revolve a plurality of strands at constant speed about a common axis, means to revolve a second plurality of strands at varying speed about the same axis, and means to lay the second plurality about the first plurality and annul their revolution whereby the strands of the first plurality form a core group of constant pitch and the strands of the second plurality form a shell group of varying 60 pitch about the core group.

10. An apparatus for combining strands to form a cable which comprises means to revolve a plurality of strands at constant speed about a common axis, means to revolve a second plurality of strands at varying speed about the same axis, and means to lay the first plurality about the second plurality and annul their revolution whereby the strands of the second plurality form 65 70 75

a core group of constant pitch and the strands of the first plurality form a shell group of varying pitch about the core group.

11. An apparatus for combining strands to form a cable which comprises a distributor member through which all of the strands pass under individual control, a second distributor member through which a part only of the strands passes under individual control, means to rotate one distributor member at constant speed, means to rotate the other distributor member at varying speed, and means to receive all of the strands from the distributor members and twist them together.
12. An apparatus for combining strands to form a cable which comprises a rotatable distributor disc provided with an individual guide for each of all of the strands, a second rotatable distributor disc provided with an individual guide for each of a part of the strands and with an aperture to pass another part freely, means to rotate the first distributor disc at constant speed, means to rotate the second distributor disc at cyclically varying speed, and a die to receive and twist together all of the strands.
13. An apparatus for combining strands to form a cable which comprises means to revolve a plurality of strands at varying speed about a common axis, means to revolve a second plurality

of strands at constant speed about the same axis, means to revolve a third plurality of strands at varying speed about the same axis, and means to lay the second plurality about the first plurality and the third plurality about the second plurality and to annul their revolution whereby the strands of the first plurality form a core group of varying pitch, the strands of the second plurality form a shell group of constant pitch about the core group, and the strands of the third plurality form a shell group of varying pitch about the first and second pluralities.

14. An apparatus for combining strands to form a cable which comprises a distributor member through which two pluralities of strands pass under individual control, a second distributor member through which one plurality only passes under individual control, a third distributor member through which a third plurality of strands passes under individual control, means to rotate one of the distributor members at varying speed, means to rotate another of the distributor members at constant speed, means to rotate the remaining one of the distributor members at varying speed, and means to receive all of the strands from the distributor member and twist them together.

VAUGHN L. JOHANNESSEN.
